COMBINATION FUSE FOR PROJECTILES

Filed July 12, 1928

Attorney

UNITED STATES PATENT OFFICE

ALFRED F. TEITSCHEID, OF WHARTON, NEW JERSEY

COMBINATION FUSE FOR PROJECTILES

Application filed July 12, 1928. Serial No. 292,154.

(GRANTED UNDER THE ACT OF MARCH 3, 1883, AS AMENDED APRIL 30, 1928; 370 O. G. 757)

The invention described herein, if patented, may be manufactured and used by or for the Government for governmental purposes, without the payment to me of any royalty thereon.

The subject of this invention is a combination fuse for projectiles.

In combination fuses which have a protruding impact striker as shown in Patent No. 1,648,603, the striker is normally partially extruded and accidental blows received thereby during storage, shipment and handling have so bent the striker that it has been impossible to move it to the inoperative position.

The present invention contemplates correction of these disadvantages in a novel manner whereby the striker is utilized to retain both detonator carriers of the fuse in the unarmed position.

The invention further relates to means for insuring functioning of the delay action firing mechanism; to a new and desirable form of plunger construction and to an arrangement of a rotor which, by the character of its mounting, will be retained in the armed position after impact.

With the foregoing and other objects in view, my invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawing, wherein:

Fig. 1 is a longitudinal sectional view of a fuse constructed in accordance with the invention;

Fig. 2 is a fragmentary longitudinal sectional view taken through the plunger at right angles to Fig. 1;

Fig. 3 is a sectional view on the line 3-3 of Fig. 1.

Referring to the drawings by numerals of reference:

The fuse consists generally of a head 5

which is in threaded engagement with a body 6 arranged for attachment to a projectile. The nose of the fuse head is bored and tapped to receive a striker casing which, for convenience of manufacture, is made in three parts, namely an outer sleeve 7 whose outer end is inturned as at 8, a base 9 retained by the outer sleeve 7 and an inner sleeve 10 whose upper end serves to limit inward movement of a striker head 11. A striker rod 12 threaded and pinned to the head 11 is formed with a threaded portion 13 and a firing pin 14. The threaded portion 13 is adapted for engagement with a threaded aperture 15 in the base 9 of the striker casing so as to retain the striker out of operation when instantaneous or quick action of the fuse is not desired. The striker may be held in its forward position against air pressure during flight by means of spring 16 which surrounds the rod 12 and is disposed within the striker casing.

The fuse head 5 is formed in its rear end with a cavity 17 into which projects the stationary firing pin 18. Within the cavity is a plunger 19 normally retained on its seat at the rear end of the cavity by a pair of springs 20 disposed in recesses 21 formed longitudinally of the plunger and preferably provided with guide thimbles 22. During assembling of the fuse, and before application of the fuse body, the plunger is maintained in its unarmed position in restraint against the action of the springs 20 by means of a bolt 23 which is secured in the fuse head and after being passed through an aperture in the plunger receives a nut 24. An aperture 25 is formed axially of the plunger through which the firing pin 14 is adapted to pass, and a second aperture is formed off center for the reception of a primer detonator 26 and a delay element 27, the flash from which may pass through a duct 28 which opens at the rear face of the plunger. The primer 26 is spaced from the forward base of the plunger so that with the fuse unarmed the point of the stationary firing pin 18 may be inserted in an opening 29 in the plunger thus being assured of striking the primer and preventing rotational movement of the plunger during its forward displacement on impact.

The plunger is positively held in the unarmed position prior to use of the fuse by virtue of the engagement of the threaded portion 13 of the striker against its outer face and this engagement is maintained by a protective cap 30 threaded to the forward end of the outer sleeve 7 of the striker casing and restraining forward movement of the striker head 11 under the action of the spring 16. During assembling of the fuse the portion 13 limits movement of the plunger in the direction of arming and prevents accidental functioning of the delay mechanism.

The cap 30 is removed when the fuse is to be used and a centrifugally releasable pin 31 is employed in the customary manner to hold the plunger safe while the projectile is in the bore of the gun.

The fuse body 6 is provided with a cavity 32 preferably formed eccentrically thereof for receiving a pivoted rotor 33 carrying a primer detonator 34 and having a recess 35 which is axially of the fuse when the rotor is held in the unarmed position by a centrifugally releasable pin 36. When the fuse is assembled the rotor is separated from the plunger by a disk 37 centrally apertured to permit passage of the firing pin which is held in the recess 35 to positively prevent arming of the rotor when the protective cap 30 is in place. When the fuse is set to function through the striker rod the firing pin will re-enter the recess 35 on set-back.

The pivot 38 of the rotor is so placed that the rotor in moving to the armed position indicated in dotted lines in Fig. 3 is caused to bear tightly against the wall of the fuse body as it is brought up against the stop pin 39. This provision is made for the purpose of establishing a sufficient restraint against the countermovement of the rotor on impact to insure that the centrifugal pin 40 will have time to react and engage behind a wing of the rotor. In order to permit tolerances in manufacture the pin 40 does not necessarily engage the rotor in the unarmed position but it is in position to hold the rotor unarmed in the event of failure of the pin 36.

The striker rod provides for quick action on impact when not threaded to its casing and when inoperative by being threaded to the casing a delay firing action will occur when the inertia plunger moves forward to bring the primer 26 into contact with the stationary firing pin 18.

I claim:

1. In a combination fuse, a normally unarmed inertia plunger carrying an element of a delay firing mechanism, a normally unarmed detonator carrier in rear of the plunger, an impact striker passing through the plunger to the detonator carrier and when in the fired position opposing movement of the plunger and carrier to armed position

and a removable cap on the nose of the fuse for holding the striker in the fired position.

2. In a combination fuse, a normally unarmed inertia plunger carrying an element of a delay firing mechanism, a normally unarmed detonator carrier in rear of the plunger, an impact striker passing through the plunger to the detonator carrier and when in the fired position opposing movement of the plunger to armed position and a removable cap on the nose of the fuse for holding the striker in the fired position. 70 75

3. In a combination fuse, a normally unarmed inertia plunger carrying an element of a delay firing mechanism, a normally unarmed detonator carrier in rear of the plunger, an impact striker passing through the plunger to the detonator carrier and when in the fired position opposing movement of the carrier to armed position and a removable cap on the nose of the fuse for holding the striker in the fired position. 80 85

4. In a combination fuse, an instantaneous and a delay action firing mechanism including normally unarmed movable detonator carriers and a removable means for securing an element of the instantaneous firing mechanism in position to oppose movement of the detonating carriers out of unarmed position. 90

5. In a fuse, a normally unarmed detonator carrier, a firing pin and removable means for securing the firing pin in position to oppose movement of the detonator out of unarmed position. 95

6. In a fuse, a housing, a plunger in the housing, a primer carrier eccentrically by the plunger and intermediate its end faces and a firing pin fixed in the housing and extending into the plunger in line with the primer when the plunger is in unarmed position. 100 105
